UNITED STATES PATENT OFFICE.

SAMUEL M. WRIGHT, OF SCHENECTADY, NEW YORK.

WATER-HEATER.

1,309,083.

Specification of Letters Patent.

Patented July 8, 1919.

Application filed October 22, 1917. Serial No. 197,780.

To all whom it may concern:

Be it known that I, SAMUEL M. WRIGHT, a citizen of the United States, residing at Schenectady, county of Schenectady, and 5 State of New York, have invented certain new and useful Improvements in Water-Heaters, of which the following is a specification.

Reference may be had to the accompanying drawings, and the reference characters marked thereon, which form a part of this specification. Similar characters refer to similar parts in the several figures therein.

This invention relates more particularly 15 to water-heaters of the gas-heated type, wherein the supply of gas to the burner is automatically regulated by variations in the water-pressure due to the opening or closing of a faucet supplied by the heater.

20 The principal object of the invention is to prevent waste of gas in the use of such a heater by regulating the supply of gas to the burner in accordance with the demand made upon the heater by a more or less 25 opened faucet or faucets.

Other objects will appear in connection with the following description.

Figure 1 of the drawings is a view partly in side elevation, partly broken away, and 30 partly in vertical section, of a water-heater embodying my invention.

Fig. 2 is a view in side elevation of the same viewed from the right-hand side, as shown in Fig. 1.

35 Fig. 3 is a view in side elevation of the gas-valve-controlling plunger detached.

Fig. 4 is a top plan view of the same.

Fig. 5 is a central longitudinal section of the upper portion of one of the flues, 40 and an adjacent broken-away portion of the upper head of the heater-casing.

Referring to the drawings wherein the invention is shown in preferred form, the casing of the heater is formed of a cylinder, 45 1, having at each end a cap or head, 2, the upper cap being surmounted by a hood, 3, from which extends a smoke-pipe 4.

The upper head has an inlet-nipple, 5, while the lower head has an outlet-nipple, 6.

50 The out-flow through the pipe, 7, is controlled in the usual manner by a faucet or faucets, not shown.

Mounted below the lower head, 2, is a main gas-burner, 8, the supply of gas to which is controlled by a valve, 9, which may 55 be of any desired form, having an operating member, 10. The supply to the valve, 9, can be further controlled if desired, by means of a cut-off valve, 11.

A pilot-light-burner, 12, is connected with 60 the gas-supply-pipe between the valves, 9 and 11.

Supported adjacent to the heater casing or body, is a water-valve-casing, 13, having an elongated cylindrical chamber provided 65 with an inlet, 14, leading to the upper end of the chamber, and with a lateral outlet, 15, intermediately of the ends of the chamber.

The inlet, 14, is connected with a water- 70 supply-pipe, not shown.

The outlet, 15, is connected by pipe, 16, with the inlet-nipple, 5, on the upper head, 2.

A plunger, 17, fitting loosely within the chamber in the valve-casing, 13, is adapted 75 to reciprocate therewithin past the outlet, 15. This plunger has its peripheral portion adjacent to the outlet, 15, cut-away or chamfered increasingly toward its upper end or the inlet-end of the chamber. 80

The plunger may be so chamfered in any desired manner; but I have shown it chamfered in the preferred manner by forming or cutting therein a longitudinal peripheral groove, 18, V-shaped in cross-section, and 85 gradually increasing in width and depth toward the upper end of the plunger.

A coil-spring, 19, is confined under compression within the chamber in the casing, 13, between the lower end of the plunger, 17, and the bottom of the chamber, said spring tending to force the plunger toward the inlet-end of the chamber. 90

A rod, 20, connected at its upper end with the plunger, 17, extends out through a stuffing-box, 21, at the lower end of the valve-casing, 13, its projecting end being connected by a link, 22, with the operating member, 10, of the gas-valve, 9, whereby reciprocating movements of the plunger, 17, 100 are transmitted to said gas-valve-operating member to vary or control the supply of gas to the main burner, 8.

A passageway, 23, is formed in the valve-

casing, 13, connecting the outlet, 15, with the lower part of the chamber within said valve-casing.

The gas-valve, 9, is so adjusted that it is 5 fully closed when the plunger, 17, is in its uppermost position, and is gradually opened by the downward movement of the plunger.

The operation of the device is as follows:

Under normal conditions, when there is no 10 demand by the house-system upon the heater, the pressure of water in the inlet-end of the chamber in the valve-casing is equalized by the pressure within the heater-body, and the outlet, 15, and the lower portion of said 15 chamber, so that the plunger, 17, is held in its uppermost position by the influence of the spring, 19.

When a demand is created upon the 20 heater by the opening of a faucet in the house-system, the pressure within the heater-body, outlet, 15 and lower part of the chamber within the valve-casing, 13, is immediately reduced, thus relieving the upward water-pressure upon the plunger, 17, 25 which thereupon yields to the greater pressure from its upper end, of the water entering the chamber through the inlet, 14, causing the plunger to be forced downward against the force of the spring, 19, so as to 30 uncover to the outlet, 15, a portion of the groove, 18, in the plunger, through which groove the water then passes from the inlet-end of the chamber to the outlet, 15, and thence through the heater-body to the supply-pipe, 7.

So long as the demand upon the heater causes the pressure of the water within the body of the heater to be materially less than the pressure of the water entering 40 through the inlet, 14, in the water-valve, the plunger, 17, will remain more or less depressed; and the greater the demand upon the heater, with the resultant greater reduction of pressure within the heater-body, 45 the greater will be the downward movement of the plunger, 17.

As the movement of the plunger is transmitted to the operating member, 10, of the gas-valve, 9, it follows that, as the demand 50 upon the heater increases, the gas-valve will be opened farther and farther, and as the demand upon the heater lessens, the pressure within the heater-body will more or less rapidly increase, causing the plunger, 55 17, to move upward with the resultant closing more or less rapidly of the gas-valve, 9. The gas is thus supplied to the burner, 8, automatically in accordance with the demands upon the heater.

60 The heater-body, has numerous flues, 24, fitted at their upper ends in apertures in the upper head, 2, and at their lower ends in apertures in the lower head, 2.

In order to obtain the maximum effect 65 of the heated gases passing upward through

the flues from the main gas-burner, 8, it is desirable to employ some flow-retarding means at the upper ends of the flues. To this end, I preferably inwardly taper the several flue-apertures in the upper head, 2, and expand the upper end of the tube into tight-fitting engagement therewith, by driving into the upper end of the tube, an inwardly-tapered flow-retarding bushing or plug, 25, which serves the double purpose of retarding the upward flow of gases through the flue, and of effecting a tight joint between the end of the flue and the head, 2.

What I claim as new and desire to secure by Letters Patent is—

1. In a device of the class described and in combination, a water-valve-casing having an elongated chamber provided with an inlet leading to one end of the chamber, and with a lateral outlet; a plunger reciprocatory within said chamber past said outlet, and having its peripheral portion adjacent to said outlet increasingly chamfered toward the inlet-end of said chamber, said plunger being automatically yieldingly movable toward the inlet-end of said chamber; a gas-valve; and an operating connection between said plunger and said gas-valve.

2. In a device of the class described and in combination, a water-valve-casing having an elongated chamber provided with an inlet leading to one end of the chamber, and with a lateral outlet; a plunger reciprocatory within said chamber past said outlet, and provided with a longitudinal peripheral groove, V-shaped in cross-section, gradually increasing in width and depth toward the inlet-end of said chamber, said plunger being automatically yieldingly movable toward the inlet-end of said chamber; a gas-valve; and an operating connection between said plunger and said gas-valve.

3. In a device of the class described and in combination, a water-valve-casing having an elongated chamber provided with an inlet leading to one end of the chamber, and with a lateral outlet intermediately of its ends; a plunger reciprocatory within said chamber past said outlet, and having its peripheral portion adjacent to said outlet increasingly chamfered toward the inlet-end of said chamber; a spring interposed between the other end of said chamber and said plunger, tending to force the plunger toward the inlet-end of said chamber; a gas-valve; and an operating connection between said plunger and said gas-valve.

4. In a device of the class described and in combination, a water-valve-casing having an elongated chamber provided with an inlet leading to one end of the chamber, and with a lateral outlet intermediately of its ends, said valve-casing being provided with a passageway communicating with said inlet, and with the other end of said chamber;

a plunger reciprocatory within said chamber, past said outlet, and provided with a longitudinal peripheral groove of gradually increasing size toward the inlet-end of said chamber; a spring interposed between the other end of said chamber and said plunger tending to force the plunger toward the

inlet-end of said chamber; a gas-valve; and an operating connection between said plunger and said gas-valve. 10

In testimony whereof, I have hereunto set my hand this 17th day of October, 1917.

SAMUEL M. WRIGHT.
